UNITED STATES PATENT OFFICE.

HERMANN ABELE, OF ZURICH, SWITZERLAND.

BUNDLING PRESS.

Application filed October 31, 1925, Serial No. 65,994, and in Germany October 21, 1924.

This invention relates to a device for pressing bundles of paper, textiles and the like, and of the kind in which the bundle is compressed between two sets of plates one of which is carried by plungers connected to a reciprocating frame.

According to the present invention the pressure frame is controlled by an endless chain which is guided over rollers and actuated by the foot lever through the medium of a pawl and ratchet mechanism, the pawls being spring-controlled and provided with arms which co-operate with the hand lever for throwing the pawls into and out of gear.

The hand lever is also connected to a mechanism whereby the initial lowering of the pressure frame is readily and quickly effected simultaneously with the operation of the pawls.

Fig. 1 of the accompanying drawings represents a side view of the machine,

Fig. 2, a horizontal section of the same,

Fig. 3, a view of the hand lever with attached mechanism, and

Fig. 4, a plan of the latter.

The machine is composed of a frame 1 which carries a top plate 2. A set of spaced brackets 3 is mounted on the top 2 and formed with supporting plates 3' for the reception of the bundles to be compressed. Another set of plates 5 is held above the plates 3' by plungers 4 which are guided in the brackets 3 and secured to a frame 6 whereby the plates 5 can be actuated for compressing the bundles against the plates 3'. As the plates are spaced from each other and raised from the top 2, the bundles can easily be tied up in their compressed state.

For controlling the frame 6, an endless chain 7 is provided which is secured to the frame and guided over a sprocket wheel 9 and over deflection pulleys 10. A weight 11 is connected to the chain as a counter-balance for the frame and the plungers, the weight being heavy enough to maintain the structure in its highest position. The sprocket wheel 9 is secured to a ratchet wheel 12, both being rotatably arranged on a shaft 8 which is carried by brackets 13 supported on a cross-bar 14 in the machine frame. On the same shaft, a U-shaped shackle 16 is arranged so that it can rock independently of the wheels. A shaft 18, held by the shackle 16, engages with its ends in slots 19 made in another shackle 20

which is arranged to rock about a shaft 21, the latter being carried by the brackets 13. The shackles 16 and 18 can be rocked by means of a treadle 22 having at its free end a foot plate 23. A pawl 17 adapted for engagement with the ratchet wheel 12, is secured to the shaft 18 which also carries, outside the shackle 16, an arm 29. A spring 44 acts on the arm 29 and tends to hold the pawl in engagement with the ratchet wheel. This is normally prevented by a lever arm 27 which for this purpose rests on the cranked end of the arm 29. The lever 27 is arranged to rock about the shaft 21 and controls a shackle 26 which normally supports an arm 25 connected to a detent pawl 24. A spring 45 tends to hold the pawl 24 in engagement with the ratchet wheel 12, such engagement being normally prevented by the shackle 26. A spring 46 maintains the treadle 22 normally in raised position.

A rod 28 connects the lever 27 with a bell-crank 30 whose opposite end is pivoted to a slotted plate 32. A hand-operated lever 33, which rocks about a pivot 47, carries a bolt 49 which engages the slot of the plate 32. It also carries a stud 35 which, in the lowest position of the lever, strikes against an inclined surface 31 on the plate 32 so as to depress the latter and operate the bell-crank 30. When the bell-crank is thus operated, the rod 28 is raised and the lever 27 turned for releasing the two pawls which then enter into engagement with the ratchet wheel 12. The lever 33 carries a roller 34 which bears against a curved arm 40 arranged on a shaft 48 and connected by means of a sleeve 51 with another curved arm 41. The latter arm engages a roller 42 carried by the frame 6.

The lever 33 is arranged at one side of the machine frame. The levers 40 and 41 and the sleeve 51 transmit the motion to the more centrally disposed roller 42, and the lever 40, moreover, serves to secure greater leverage on the plungers.

After the bundle has been adjusted between the presser plates 3' and 5, the lever 33 is depressed so as to rock the arms 40 and 41. Acting on the roller 42, the arm 41 forces the plates 5 down against the bundle. As the stud 35 engages the plate 32 and operates the bell-crank 30, the pawls 17 and 24 are released so that the compression of the bundle can now be effected through the medium of the ratchet mechanism which for

this purpose is operated by means of the treadle. After the bundle has been tied, the lever 33 is operated for disengaging the pawl from the ratchet wheel 12. For this purpose 5 the bolt 49 engages the plate 32 at the upper end of its slot, the rod 28 being thereby depressed and the lever 27 forcibly applied to the arms 29 and 25 of the pawls. As the wheels 12 and 9 can then turn freely, the 10 plungers will be raised by the weight 11. The upward movement of the plungers is limited by the arms controlled by the lever 33 for which latter an abutment 43 is provided. To allow the bolt 49 to be raised 15 slightly beyond the position determined by the abutment 43, if it should be required for disengaging the pawls from the ratchet wheels, the lever 33 is jointed so that it can bend about the shaft which carries the roller 20 34. The outer portion of the lever is double-armed and engages the inner portion by means of a lug 50 so as to be rigidly supported by the inner portion for downward movement. The inner end of the outer portion 25 is pointed for engagement with a V-shaped notch made in a slide 36. This slide has a slot 37 whereby it is guided on a block 43' connected to the inner portion 33' of the lever, and it is pressed forward by a lever 39 which is controlled by a strong spring 38. The lever 39 and the spring 38 are both carried by the lever portion 33'. When lifting 30 force is applied to the free end of the lever 33 after the portion 33' has come to rest 35 against the abutment 43, the slide 36 yields so as to allow the lever to bend about the pivot 34. Under the action of the spring 38 and the bevelled abutting surfaces of the slide and the lever, the parts of the latter 40 will be restored to their normal relative position as soon as the part 33 is released:

I claim:—

1. A bundle press of the character described, comprising a machine frame, a 45 presser frame guided vertically in said ma-

chine frame, an endless travelling chain guided vertically in the machine frame and connected to said presser frame, a weight connected to the chain so as to maintain the presser frame normally in raised position, a 50 pawl-and-ratchet mechanism for operating said chain so as to lower the presser frame, a foot lever for operating said pawl-and-ratchet mechanism, a hand lever for lowering the presser frame initially, means for 55 maintaining the pawl-and-ratchet mechanism normally inoperative, and means controlled by said hand lever for rendering said mechanism operative as the lever attains the end of the lowering stroke and for restoring the 60 mechanism to inoperative condition at the end of the return stroke.

2. A bundle press of the character described, comprising a machine frame, a presser frame guided vertically in said machine frame, an endless travelling chain guided vertically in the machine frame and connected to said presser frame, a weight connected to the chain so as to maintain the presser frame normally in raised position, a 65 pawl-and-ratchet mechanism for operating said chain so as to lower the presser frame, a foot lever for operating said pawl-and-ratchet mechanism, a jointed hand lever, 70 spring controlled means for rendering said hand lever rigid within given limits, means for supporting said hand lever on the presser frame so that the latter can be initially lowered by means of the lever, means for maintaining the pawl-and-ratchet mechanism 75 normally inoperative, means controlled by said hand lever for rendering said mechanism operative as the lever attains the end of the lowering stroke and for restoring the mechanism to inoperative condition at the 80 end of the return stroke, the hand lever being enabled to bend about its joint for the setting of the pawl-and-ratchet mechanism 85 after the stoppage of the presser frame.

HERMANN ABELE.
